(57) **CLAIM**

The ornamental design for a display screen with interface for geo-networking website, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen with interface for geo-networking website.

The broken line showing of a display screen or portion thereof and graphical elements within the display screen are not part of the claimed design.
